UNITED STATES PATENT OFFICE.

MARIANO FORTUNY, OF VENICE, ITALY.

STAGE ILLUMINATION WITH INDIRECT LIGHT.

SPECIFICATION forming part of Letters Patent No. 698,924, dated April 29, 1902.

Application filed April 19, 1901. Serial No. 56,629. (No model.)

To all whom it may concern:

Be it known that I, MARIANO FORTUNY, painter, a subject of the King of Spain, residing at Venice, Italy, have invented certain new and useful Improvements in or Relating to Stage Illumination with Indirect Light, (for which I have obtained Letters Patent of the Kingdom of Italy, Reg. Att., Vol. CXXX, No. 170, under application filed on October 22, 1900,) of which the following is a full and clear specification.

My invention relates to a system of illumination of the stage and scenery in theaters and like places of entertainment.

In existing systems of scenic lighting the blending and diffusion of colors is very limited, as it depends on the color of the screens forming the envelops of the footlights or other source of light. In making use of electric incandescent lamps with red-glass globes, for example, it is impossible to vary the tint or shade of the color afforded by these lamps.

In order to obtain a different shade or color effect in the illumination, it is necessary to employ auxiliary series of lamps having the required shade of glass screens or envelops. In the use of arc-lamps with multicolored transparent screens, the colors of which are successively interposed in the path of the rays of light from the lamp, it is not possible to obtain an effect in which the colors are uniformly blended.

Dioptric globes have been employed with the object of distributing the arc-light in a manner that can be utilized with better results than according to the systems above mentioned; but the cost of these globes and the difficulty of coloring them in a variable manner have prohibited their use.

The object of my invention is to avoid the above-mentioned difficulties and to provide a system of scenic lighting by reflected light which admits of the use of arc-lamps instead of the much more costly electric incandescent lamps and to obtain blending of colors which are impossible with existing systems.

My invention consists in a system of stage illumination in which the light from a source is reflected from an irregular surface which is diversely colored and movable across the

path of the rays of light from the source, thereby producing a uniform blending and distribution of the irregularly reflected and colored light.

Referring now to the accompanying drawings, which illustrate one form of my invention, Figure 1 is a diagrammatic view of a source of light and a reflecting-screen of the type I employ in my invention. Fig. 2 represents a reflecting-screen on a larger scale. Fig. 3 is a section through a theater-stage fitted with my arrangement of stage illumination. Fig. 4 is a perspective view of the stage in Fig. 3. Fig. 5 is the section of a theater-stage fitted with one of the present modes of stage illumination, and Fig. 6 is a perspective view of the same stage.

Referring to the above figures, *a* is any source of light, preferably white light. *b* denotes rays emanating from *a* and reflecting irregularly on *c*. *g* is the parabolic reflector intended to gather the luminous rays and to project them upon the zone *i i* of the reflecting-screen *d e*, which has a surface slightly roughened and may be made of tin, aluminum, paper, silk, satin, or other suitable material colored and obscured and suitably inclined relatively to the direction of the luminous rays coming from the source *a* to reflect them from its lighted zone *i i*, completely diffused and colored, onto the stage or scenery required.

f f are rollers upon which the surface winds and unwinds. The two rollers actuated by a rotary movement in the same direction determine the development of the surface, which thus presents to the rays from the source *a* all its parts successively colored or obscured.

In Figs. 3 and 4, *x* represents the stage; *z*, the place for the orchestra; *y*, the place for the fauteuils; *p*, the sources of light; *q*, the surfaces intended to reflect upon the roof and back of the stage the luminous rays emanated from *p* and which would otherwise be dispersed. *w* is the side working corridor.

It is evident that the illuminating groups constituted in conformity with the present invention by a luminous source utilized by a reflector upon the moving surface, substituting successively its different parts, could be

placed in the same places of the stage where the present luminous sources are usually placed.

The movement of the surfaces in question can be effected by manual or mechanical power.

It is quite understood that the present arrangement or system, the special object of which is to use arc-lamps, can also in certain cases be extended to incandescent lamps.

Having now particularly described and ascertained the nature of my said invention and in what manner the same is to be performed, I declare that what I claim is—

15 1. In a stage-illuminating apparatus, a movable reflector-screen having a diversely-colored surface and means for directing rays of

light directly onto said colored surface, and the latter serving to direct colored rays onto a desired object.

2. In a stage-illuminating apparatus, a reflector-screen having a diversely-colored, irregular surface, a source of light, a reflector arranged to receive the light-rays and to project the same directly onto said colored surface, and the latter serving to direct colored rays onto a desired object.

In witness whereof I have hereunto set my hand in the presence of two witnesses.

MARIANO FORTUNY.
